**FLUID OPERATED PUMP WITH SEPARATE,
ALIGNED PUMP AND ENGINE VALVE
UNITS**

Clarence J. Coberly, San Marino, and Val Kogut, Compton, Calif., assignors to Kebe, Inc., Huntington Park, Calif., a corporation of California

Filed Aug. 9, 1960, Ser. No. 48,541
11 Claims. (Cl. 103—46)

The present invention relates in general to fluid operated well pumps and, more particularly, to a fluid operated well pump and pumping system of the type which includes separate pump and engine valve units and in which the engine valve unit is installable in and removable from the well independently of the pump unit, a fluid operated pump and pumping system of this type being disclosed and claimed in co-pending patent application Serial No. 598,785, filed July 19, 1956 in the name of Clarence J. Coberly, now Patent No. 2,949,857, issued August 23, 1960, the disclosure of which is incorporated herein by reference.

The aforementioned patent discloses a fluid operated pumping system incorporating separate pump and engine valve units wherein these units are located side-by-side in the well when in their operating positions and are installable in and removable from the well independently through pump and valve tubings, preferably by circulating them into or out of the well hydraulically. This arrangement, of course, requires that the pump and valve tubings be set in the well in side-by-side relation.

A primary object of the present invention is to provide a fluid operated pumping system utilizing separate pump and engine valve units wherein these units are located in axial, i.e., vertical, alignment so that a concentric tubing system, rather than a parallel, i.e., side-by-side, tubing system, may be employed. Thus, the present invention permits the utilization of separate pump and engine valve units in a well bore which is too small to accept a parallel tubing system, or wherever it is desired to utilize a concentric tubing system for any reason, which is an important feature.

An important object of the invention is to provide a pumping system wherein the engine valve unit, when in its operating position, is located above, and in axial alignment with, the pump unit, and wherein the engine valve unit is installable and removable independently of the pump unit.

Another important object of the invention is to provide a pumping system wherein the independently installable and removable engine valve unit is movable between the surface and its operating position in the well through a valve tubing which forms the innermost tubing of a concentric tubing system, the engine valve unit preferably being movable through the valve tubing hydraulically, although it may also be raised and lowered on a wire line, for example.

Another object is to provide a pumping system of the foregoing nature wherein the pump unit is a set unit, as opposed to a free unit, located within a bottom hole housing at the lower end of an outer tubing which encircles the valve tubing, the valve tubing serving as a supply tubing for conveying operating fluid, such as clean crude oil, under pressure downwardly to the pump and engine valve units, and the outer tubing serving as a production tubing for well fluid pumped by the pump unit and as a return tubing for spent operating fluid.

With the foregoing construction, the engine valve unit may be removed quickly and easily for service or repair whenever required, and may be just as quickly re-installed, or replaced with another engine valve unit, all without disturbing the pump unit itself. This is an ex-

2

tremely important feature since it requires a minimum of down time for removal and reinstallation, or removal and replacement, of the component of the fluid operated pump which most frequently requires service, repair, or replacement, such component, of course, being the engine valve unit. The pump unit, on the other hand, requires service, repair, or replacement, much less frequently.

Another object of the invention is to provide a bottom hole housing which is connected to the lower end of, and in effect forms a downward continuation of, the outer tubing, the pump unit being lowerable into its operating position in the bottom hole housing through the outer tubing, which tubing is therefore sometimes referred to herein as the pump tubing.

15 A further object of the invention is to provide a pumping system wherein the pump unit is connected to the lower end of the valve tubing and is lowerable through the pump tubing into its operating position in the bottom hole housing by means of the valve tubing as sections 20 are added to the valve tubing at the surface. Of course, the pump unit may be removed from the well by reversing this process.

25 Still another object is to connect the pump unit to the lower end of the valve tubing through a valve housing which provides a valve chamber for receiving the engine valve unit when the latter is circulated downwardly through the valve tubing into its operating position in the well.

30 Yet another object of the invention is to provide a pumping system wherein the necessary passages for interconnecting the engine valve unit and the pump unit are formed in the bottom hole housing.

35 The foregoing objects, advantages, features and results of the present invention, together with various other objects, advantages, features and results thereof which will be evident to those skilled in the fluid operated pump art in the light of this disclosure, may be achieved with the exemplary embodiment of the invention described in detail hereinafter and illustrated in the accompanying 40 drawings, in which:

45 FIGS. 1 and 2 are semidiagrammatic views illustrating a fluid operated pumping system which embodies the invention and respectively showing two different sets of operating positions for certain components of a fluid operated pump of the invention;

FIG. 3 is a vertical sectional view of the upper end of an actual physical embodiment of a fluid operated pump and pumping system of the invention;

FIG. 4 is a downward continuation of FIG. 3;

FIG. 5 is a downward continuation of FIG. 4;

FIG. 6 is a downward continuation of FIG. 5;

FIG. 7 is a horizontal sectional view taken along the arrowed line 7—7 of FIG. 3;

FIG. 8 is a fragmentary, developed elevational view, 55 taken as indicated by the arrowed line 8—8 of FIG. 7, and corresponds to FIG. 3;

FIG. 9 is a downward continuation of FIG. 8 and corresponds to FIG. 4; and

FIG. 10 is a fragmentary downward continuation of 60 FIG. 9, portions having been removed to reduce the width of the figure, and corresponds to FIG. 5 of the drawings.

Initially, the invention will be considered herein in connection with the semidiagrammatic views of FIGS. 1 and 2. However, the description of the semidiagrammatically-illustrated embodiment of FIGS. 1 and 2 will be equally applicable to the actual physical embodiment illustrated in the subsequent figures.

Referring to FIGS. 1 and 2 of the drawings, the numerals 20 and 22 respectively designate concentric inner and outer tubings, respectively referred to hereinafter as pump and valve tubings, which are suspended in a

well bore, not shown, from a well head, not shown, in the conventional manner. As will become apparent, the valve tubing 22 serves as a supply tubing for conveying operating fluid under pressure downwardly in the well from the surface, while the pump tubing 20 serves to convey production fluid from the well and spent operating fluid upwardly to the surface. Thus, the pump tubing 20 serves as a combined production tubing and return tubing for spent operating fluid in the particular construction illustrated, it being understood, however, that the production fluid and the spent operating fluid may be conveyed to the surface through separate production and return tubings concentrically related to the supply tubing 22, as disclosed in Patent No. 2,589,669, to Clarence J. Coberly, issued March 18, 1952.

Connected to the lower end of and forming a downward extension of the pump tubing 20 is a tubular bottom hole housing 24 having at its lower end an annular seat 26 for the lower end of a fluid operated pump unit 28. Interconnecting the upper end of the pump unit 28 and the lower end of the valve tubing 22, and disposed within the bottom hole housing 24, is a valve housing 30 for a fluid operated engine valve unit 32 which controls the operation of the pump unit. As will be apparent, the pump unit 28 and the valve housing 30 may be lowered into the bottom hole housing 24, and the lower end of the pump unit seated on the annular seat 26, by means of the valve tubing 22. The pump unit 28 and the valve housing 30 may also be removed from the well by means of the valve tubing 22. The engine valve unit 32 is adapted to be circulated into and out of the well through the valve tubing 22 hydraulically as will be described in more detail hereinafter, the lower end of the engine valve unit being seated on an annular seat 34 at the upper end of the pump unit 28 when the engine valve unit is in its operating position within the valve housing 30.

The fluid operated pump unit 28 is virtually identical to that illustrated in FIGS. 5, 6 and 15 to 32 of Patent No. 2,949,857 so that a complete description thereof herein is unnecessary. Briefly, the pump unit 28 includes a pump body 36 having therein axially, i.e., vertically, reciprocable, interconnected engine and pump piston means comprising a single axially reciprocable plunger 38 provided with upper and lower plunger elements 40 and 42 disposed in upper and lower cylinders 44 and 46 and interconnected by a rod 48 extending through an intervening bore 50. The plunger 38 is provided therethrough with a central axial passage 52 for production fluid to be pumped. The passage 52 communicates at its lower end with a well fluid inlet 54 in the pump body 36, the inlet 54, in turn, communicating with a well fluid inlet 56 in the bottom hole housing 24. Reverse flow through the inlet 54 is prevented by a standing valve 58. Reverse flow through the passage 52 during the upward, working stroke of the plunger 38 is prevented by a working valve 60 carried by the plunger. The upper end of the axial passage 52 through the plunger 38 communicates with an outlet 62 in the pump body 36, reverse flow through this outlet being prevented by an upper standing valve 64. The outlet 62 is connected in fluid communication with the pump tubing 20 above the bottom hole housing 24 by a production fluid passage means 66 in the bottom hole housing.

As will be apparent, during the upward working stroke of the plunger 38, the working valve 60 is closed and the plunger displaces production fluid upwardly past the upper standing valve 64 through the production fluid passage means 66 into the pump tubing 20. At the same time, the plunger 38 draws in additional fluid from the well past the lower standing valve 58. During the downward or return stroke of the plunger 38, the standing valves 58 and 64 are closed and the working valve 60 is open so that well fluid is merely transferred from below the plunger through the axial passage 52 into the upper cylinder 44 above the plunger.

Considering the manner in which the plunger 38 is

10 15

reciprocated to produce its working and return strokes, the annular area at the lower end of the upper plunger element 40 is constantly exposed to the operating fluid pressure in the valve tubing 22 through an operating fluid passage means 68 formed in the bottom hole housing 24 and connecting the lower end of the upper cylinder 44 to the interior of the valve housing 30 above the engine valve unit 32. As will be described hereinafter, the annular area at the upper end of the lower plunger element 42 is alternately exposed to the operating fluid pressure and to the pressure of the production fluid and the spent operating fluid in the pump tubing 20 through a passage means 70 in the bottom hole housing 24. The passage means 70 communicates at its lower end with the upper end of the lower cylinder 46 and communicates at its upper end with the engine valve unit 32, which alternately connects the passage means 70 to the valve tubing 22 and the pump tubing 20 in a manner to be described. As explained in Patent No. 2,949,857, the annular area at the upper end of the lower plunger element 42 exceeds the annular area at the lower end of the upper plunger element 40. Consequently, the plunger 38 moves downwardly through its return stroke when the slightly larger annular area at the upper end of the lower plunger element 42 is exposed to the operating fluid pressure in the valve tubing 22. Of course, the plunger 38 moves upwardly through its working stroke when the upper end of the lower plunger element 42 is connected to the pump tubing 20.

The engine valve unit 32, and its relation to the pump unit 28, are also substantially as illustrated in FIGS. 5, 6 and 15 to 32 of Patent No. 2,949,857, and as described in the corresponding portion of the specification thereof. Consequently, a complete description herein is unnecessary.

Briefly, the engine valve unit 32 includes a valve body 72 having therein an axially, i.e., vertically, reciprocable valve member 74 provided therein adjacent its upper end with an external annular channel 76. When, as shown in FIG. 1 of the drawings, the valve member 74 is in its upper position, the annular channel 76 bridges the passage means 70 leading to the upper end of the lower cylinder 46 and a branch passage means 78 which communicates with a passage means 80 leading to the pump tubing 20, the passage means 80 being formed in the bottom hole housing 24 and the branch passage means 78 being formed in the bottom hole housing, the valve housing 30 and the valve body 72. Under these conditions, the pressure in the pump tubing 20 is applied to the upper end of the lower plunger element 42 and, since the operating fluid pressure in the valve tubing 22 is always applied to the lower end of the upper plunger element 40 through the operating fluid passage means 68, the plunger 38 moves upwardly through its working stroke, as indicated by the arrow 82.

On the other hand, when the valve member 74 is in its lower position, as shown in FIG. 2 of the drawings, the upper end of the valve member is below the upper end of the passage means 70 leading to the upper end of the lower cylinder 46, whereby the operating fluid pressure in the valve tubing 22 is applied, through the passage means 70, to the upper end of the lower plunger element 42. Under these conditions, the plunger 38 moves downwardly through its return stroke, as indicated by the arrow 84, because of the fact that the area of the upper end of the lower plunger element 42 is slightly larger than the area of the lower end of the upper plunger element 40.

As the plunger 38 reaches the end of its working stroke, the valve member 74 is hydraulically shifted downwardly into its lower position to reverse the direction of motion of the plunger, and, as the plunger reaches the end of its return stroke, the valve member 74 is hydraulically shifted upwardly into its upper position to once again reverse the direction of plunger motion, all as

fully described in Patent No. 2,949,857. Therefore, a complete description herein is unnecessary.

Briefly, as the plunger 38 approaches the end of its working stroke, a control groove 86 in the rod 48 bridges the lower ends of the passage means 80 and a control passage means 88, this control passage means leading upwardly through the bottom hole housing 24 and communicating at its upper end with the engine valve unit 32. Under these conditions, the lower pressure in the pump tubing 20 is transmitted to the engine valve unit 32, by way of the passage means 80, the groove 86 and the control passage means 88, to shift the valve member 74 downwardly into its lower position, as fully described in Patent No. 2,949,857. This causes the plunger 38 to begin its return stroke.

As the plunger 38 approaches the end of its return stroke, a control groove 90 in the rod 48 connects the lower end of the upper cylinder 44 to the lower end of the control passage means 88. Since the lower end of the upper cylinder 44 always contains fluid at the operating fluid pressure in the valve tubing 22 by virtue of the presence of the operating fluid passage means 68, the control passage means 88 under these conditions transmits the operating fluid pressure to the engine valve unit 32 to cause the valve member 74 to shift upwardly into its upper position, again as fully described in Patent No. 2,949,857. This causes the plunger 38 to begin its working stroke.

The foregoing completes the description of the structure of the fluid operating pumping system of the invention, as semidiagrammatically shown in FIGS. 1 and 2 of the drawings, and the description of the operation thereof when the engine valve unit 32 is in its operating position wherein it is seated on the annular seat 34 therefor at the upper end of the pump unit 28. The manner in which the engine valve unit 32 is hydraulically installed and removed will now be considered, still in connection with FIGS. 1 and 2 of the drawings.

In order to install the engine valve unit 32, it is merely necessary to drop it into the upper end of the valve tubing 22 and to circulate it downwardly through the valve tubing into its operating position within the valve housing 30 by introducing operating fluid into the valve tubing above the engine valve unit, it being understood that the tubing system is filled with fluid under such conditions and that such fluid is prevented from escaping into the well by the standing valves 64 and 58. It is merely necessary to introduce operating fluid into the valve tubing 22 above the engine valve unit 32 at a slight pressure to circulate the engine valve unit downwardly into its operating position, the fluid in the valve tubing beneath the engine valve unit 32 being displaced into the pump tubing 20 by way of the production fluid passage means 66.

To remove the engine valve unit 32 for service, repair, or replacement, it is merely necessary to reverse the flow through the tubing system. In other words, fluid is introduced into the upper end of the pump tubing 20 to produce a downward flow of fluid through the pump tubing, such downward flow continuing downwardly through the production fluid passage means 66 and thence upwardly into an axial passage 92 through the annular seat 34 for the engine valve unit. The upward flow into the axial passage 92 unseats the engine valve unit 32 and causes it to move upwardly out of the chamber therefor provided by the valve housing 30 and into the valve tubing 22. Continued downward flow of fluid through the pump tubing 20 results in circulation of the engine valve unit 32 upwardly through the valve tubing 22 to the surface.

The engine valve unit 32 and the valve tubing 22 are of relatively small diameter so that a relatively small volume of fluid is required in circulating the engine valve unit into and out of the well. Consequently, the engine valve unit 32 can be removed and reinstalled, or a replacement engine valve unit can be installed, with a mini-

mum of down time for the pumping system and with a minimum of fluid, which are important features of the invention.

As previously explained, the engine valve unit 32 is much more susceptible to wear than is the pump unit 28 so that it may be necessary to remove and replace the engine valve unit at frequent intervals, whereas it normally is necessary to remove and replace the pump unit 28 only at infrequent intervals. Thus, the ease and rapidity with which the engine valve unit 32 can be removed and replaced, without disturbing the pump unit 22, is an important feature. Of course, if service, repair or replacement of the pump unit 28 is ultimately required, it can be removed by means of the valve tubing 22.

15 The present invention attains the foregoing advantages of the independently removable, separate engine valve unit 32 with the concentric system of tubings 20 and 22, which requires a minimum amount of space in the well. Thus, the invention permits utilizing the advantages of the independently removable, separate engine valve unit 32 in slim holes, or in any other installation wherein a concentric tubing system is desired for any reason, which is an important feature.

20 Turning now to FIGS. 3 to 10 of the drawings, the structure of the actual physical embodiment illustrated therein will, for the most part, be clear from the foregoing description. Consequently, it will be considered only briefly herein and, to avoid the application of unnecessary reference numerals to the drawings, various radial ports, 25 annular grooves, and the like, constituting the upper and lower ends of the passage means 66, 68, 70, 80 and 88 will be discussed without applying reference numerals thereto.

25 The bottom hole housing 24, which is connected at its upper end to the lower end of the pump tubing 20 in a manner not specifically shown in FIGS. 3 to 10, includes inner and outer tubes or sleeves 94 and 96 which are press fitted together and which cooperate to form the vertical portions of the various passage means 66, 68, 70, 80 and 88. More particularly, the vertical portions of these passage means are formed by external longitudinal grooves in the inner sleeve 94, the outer sides of such grooves being closed by the outer sleeve 96. As best shown in FIG. 7 of the drawings, each of the passage means 66, 30 68, 70 and 80 is formed by two circumferentially spaced longitudinal grooves in the inner sleeve 94, the control passage means 88 being formed by one such groove.

35 Considering the foregoing passage means in a little more detail, the upper ends of the longitudinal or vertical grooves forming the production fluid passage means 66 communicate with the interior of the inner sleeve 94, and thus with the interior of the pump tubing 20 thereabove, through radial ports in the inner sleeve, as will be clear from the upper end of FIG. 3. Referring to the 40 lower end of this figure, and to the upper end of FIG. 4, the lower ends of the vertical grooves forming the production fluid passage means 66 communicate through radial ports in the inner sleeve 94 and the valve housing 30 with the upper end of an annulus around an upward extension 98 of the upper end of the pump body 36. The lower end of this extension houses the standing valve 45 64 and the upper end thereof provides the annular seat 34 for the engine valve unit 32.

45 As shown a little above the middle of FIG. 3, the upper ends of the vertical grooves which form the operating fluid passage means 68 communicate through radial ports and annular grooves in the inner sleeve 94 and the valve housing 30 with an annulus around the upper end of the valve body 72, such annulus communicating 50 with the lower end of the valve tubing 22 so that it, during normal operation, always contains operating fluid under pressure. As shown at the upper end of FIG. 4, the lower ends of the vertical grooves forming the operating fluid passage means 68 communicate through radial ports 55 in the inner sleeve 94 with an annulus 100 between the

inner sleeve and the pump body 36, such annulus, as shown at the upper end of FIG. 5, communicating at its lower end with the lower end of the upper cylinder 44 through radial ports in the pump body.

As shown substantially at the middle of FIG. 3, the upper ends of the vertical grooves forming the passage means 70 communicate with the engine valve unit 32 through radial ports and annular grooves in the valve housing 30 and the inner sleeve 94. The lower ends of the vertical grooves forming the passage means 70 communicate, as shown near the lower end of FIG. 5, with the upper end of the lower cylinder 46 through radial ports and annular grooves in the pump body 36 and the inner sleeve 94 and an annular clearance 101 around the rod 48.

Referring to the upper end of FIG. 3, the vertical grooves forming the passage means 80 communicate at their upper ends with the interior of the inner sleeve 94, and thus with the pump tubing 20, through radial ports in the inner sleeve. The branch passage means 78 interconnecting the passage means 80 comprises, as shown at about the middle of FIG. 3, radial ports and annular grooves in the inner sleeve 94 and in the valve housing 30. The vertical grooves forming the passage means 80 continue downwardly and, as shown at about the middle of FIG. 5, communicate with the bore 50 for the rod 48 through radial ports and annular grooves in the inner sleeve 94 and the pump body 36. The vertical grooves forming the passage means 80 continue downwardly and, as shown at the bottom of FIG. 5, communicate through radial ports in the inner sleeve 94 with an annulus 102 located between the inner sleeve 94 and the pump body 36 and extending all the way down to the lower end of the pump unit 28; as will be clear from FIG. 6. With this construction, the fluid pressure in the pump tubing 20 is applied to an annular area 104 at the bottom of the pump unit 28 substantially equal to an offsetting annular area 106, shown at the top of FIG. 3, at the upper end of the valve housing 30. Thus, the pump unit 28 is substantially hydraulically balanced in the vertical direction with respect to the fluid pressure in the pump tubing 20. It should be noted, however, that the area under the pump unit 28 where it seats in the tapered seat 26 is exposed to well pressure through the passage 56. Thus the pump unit 28 is firmly held against the seat 26 by the downward force due to the difference between the pressure in the tubing 20 and that in the inlet 56. Also part of the weight of the tubing 22 is carried by this seat.

The single vertical groove forming the control passage means 88 communicates with the engine valve unit 32, as shown slightly below the middle of FIG. 3, through radial ports and annular grooves in the inner sleeve 94 and the valve housing 30. At its lower end, the control passage means 88, as shown above the middle of FIG. 5, communicates with the interior of the bore 50 for the rod 48 through radial ports and annular grooves in the inner sleeve 94 and the pump body 36.

Referring to FIG. 3 of the drawings, an O-ring 108, carried by the valve housing 30 and engaging the inner sleeve 94 of the bottom hole housing 24 when the pump unit 28 and the valve housing 30 are in their operating positions, separates the upper ends of the production fluid passage means 66 and the operating fluid passage means 68. Similarly, an O-ring 110 separates the upper ends of the passage means 68 and 70, an O-ring 112 separates the upper end of the passage means 70 and the branch passage means 78, an O-ring 114 separates the branch passage means 78 and the upper end of the control passage means 88, and an O-ring 116 separates the upper end of the passage means 88 from the lower end of the passage means 66. Referring to FIG. 4 of the drawings, a similar O-ring 118, located at the junction of the valve housing 30 and the pump body 36, separates the lower end of the passage means 66 from the lower end of the passage means 68.

Turning to FIG. 5 of the drawings, an O-ring 120, carried by the pump body 36 and engaging the inner sleeve 94, separates the lower end of the operating fluid passage means 68 from the lower end of the control passage means 88. Similarly, an O-ring 122 separates the lower end of the control passage means 88 from the passage means 80. Similar O-rings 124 and 126 isolate the lower end of the passage means 70. As shown in FIG. 5, the pump body 36 includes a liner 128 through which the rod 48 extends and which includes a vertical groove 130 communicating at its upper end with the lower end of the upper cylinder 44, and thus with the lower end of the operating fluid passage means 68. The groove 130 communicates with the inner sides of the annular grooves containing the O-rings 120, 122 and 124 so that these O-rings are constantly biased outwardly into engagement with the inner sleeve 94 by the operating fluid pressure.

As shown in FIG. 6 of the drawings, a bottom shoe 132, which forms part of the bottom hole housing 24, is connected to the lower end of the inner sleeve 94 of the bottom hole housing. This bottom shoe provides the annular seat 26 for the pump unit 28 and provides the inlet 56 communicating with the well.

Although an exemplary embodiment of the invention has been disclosed herein for purposes of illustration, it will be understood that various changes, modifications and substitutions may be incorporated therein without departing from the spirit of the invention as defined by the claims which follow.

What is claimed is:

1. In a fluid operated pump for a well, the combination of: a fluid operated pump unit located in the well and including a pump body having therein fluid operated engine means and pump means operable by said engine means; and a separate engine valve unit located in the well in vertical alignment with said pump unit and including a valve body which is movable vertically relative to said pump body and which has therein movable engine valve means for controlling the operation of said engine means.

2. In a fluid operated pump for a well, the combination of: a fluid operated pump unit located in the well and including a pump body having therein reciprocable, interconnected engine and pump piston means, said engine and pump piston means being axially reciprocable in said pump body by an alternating fluid pressure differential applied to said engine piston means; and a separate engine valve unit located in the well in axial alignment with said engine and pump piston means and including a valve body which is movable vertically relative to said pump body and which has therein movable engine valve means for applying an alternating fluid pressure differential to said engine piston means so as to axially reciprocate said engine and pump piston means.

3. In a fluid operated pump for a well, the combination of: a fluid operated pump unit located in the well and including a pump body having therein reciprocable, interconnected engine and pump piston means, said engine and pump piston means being axially reciprocable in said pump body by an alternating fluid pressure differential applied to said engine piston means; and a separate engine valve unit located in a well above and in axial alignment with said engine and pump piston means and including a valve body which is movable vertically relative to said pump body and which has therein movable engine valve means for applying an alternating fluid pressure differential to said engine piston means so as to axially reciprocate said engine and pump piston means.

4. In a fluid operated pumping system, the combination of: a fluid operated pump unit disposed in a well and including a pump body having therein reciprocable, interconnected engine and pump piston means; a separate fluid operated valve unit disposed in the well above and in alignment with said pump unit, said valve unit including a valve body which is movable vertically relative to

said pump body and which has therein movable engine valve means for applying an alternating fluid pressure differential to said engine piston means to reciprocate said engine and pump piston means; means, including a supply tubing set in the well, for conveying operating fluid under pressure downwardly to said units; and means for conveying production fluid discharged by said pump piston means and spent operating fluid upwardly from said units.

5. In a fluid operated pumping system, the combination of: concentric pump and valve tubings set in a well with said valve tubing within said pump tubing; a fluid operated pump unit in the well in alignment with said pump and valve tubings and below said valve tubing, said pump unit including a pump body having therein movable interconnected engine and pump piston means; and a fluid operated valve unit movable through said valve tubing into an operating position in the well above and in axial alignment with said pump unit, said valve unit including a valve body having therein movable engine valve means for applying an alternating fluid pressure differential to said engine piston means to reciprocate said engine and pump piston means.

6. In a fluid operated pumping system, the combination of: concentric pump and valve tubings set in a well with said valve tubing within said pump tubing; a bottom hole housing connected to the lower end of said pump tubing; a fluid operated pump unit in said bottom hole housing below and connected to the lower end of said valve tubing, said pump unit including a pump body having therein movable interconnected engine and pump piston means; a fluid operated valve unit movable through said valve tubing into an operating position in the well above and in axial alignment with said pump unit, said valve unit including a valve body having therein movable engine valve means for applying an alternating fluid pressure differential to said engine piston means to reciprocate said engine and pump piston means; and means for moving said valve unit from its operating position in the well upwardly through said valve tubing to the surface.

7. In a fluid operated pumping system, the combination of: concentric pump and valve tubings set in a well with said valve tubing within said pump tubing; a bottom hole housing connected to the lower end of said pump tubing; a fluid operated pump unit in said bottom hole housing below and connected to the lower end of said valve tubing, said pump unit including a pump body having therein movable interconnected engine and pump piston means; a fluid operated valve unit movable through said valve tubing into an operating position in the well above and in axial alignment with said pump unit, said valve unit including a valve body having therein movable engine valve means for applying an alternating fluid pressure differential to said engine piston means to reciprocate said engine and pump piston means; and means for hydraulically moving said valve unit from its operating position in the well upwardly through said valve tubing to the surface.

8. In a fluid operated pumping system, the combination of: a bottom hole assembly set in a well and providing an upwardly facing valve chamber; a valve tubing set in the well and communicating at its lower end with said valve chamber; a fluid operated pump unit forming part of said bottom hole assembly and located below and in alignment with said valve chamber, said pump unit including a pump body having therein movable intercon-

nected engine and pump piston means; and a fluid operated valve unit separate from said pump unit and movable between the surface and said valve chamber through said valve tubing, said valve unit including a valve body having therein movable engine valve means for applying an alternating fluid pressure differential to said engine piston means to reciprocate said engine and pump piston means.

9. In a fluid operated pump for a well, the combination of: a pump unit located in the well and including a pump body having therein movable interconnected engine and pump piston means having an axial passage therethrough for the upward flow of fluid pumped by said pump piston means; a separate engine valve unit located in the well above and in axial alignment with said pump unit and including engine valve means for applying an alternating fluid pressure differential to said engine piston means, said valve unit including a valve body in which said engine valve means is disposed and which is movable vertically relative to said pump body; and bypass passage means for the upward flow of fluid pumped by said pump piston means communicating with the upper end of said axial passage and located alongside said valve unit.

10. In a fluid operated pumping system for a well, the combination of: a fluid operated pump unit located in the well and including a pump body having therein movable fluid operated engine means and pump means operable by said engine means; a valve housing above and in axial alignment with and connected to the upper end of said pump body; a valve tubing above and in axial alignment with and connected at its lower end to said valve housing; and a fluid operated valve unit movable downwardly through said valve tubing into said valve housing and including a valve body having therein engine valve means for controlling the operation of said engine means when said valve unit is in said valve housing.

11. In a fluid operated pumping system for a well, the combination of: a bottom hole housing in the well; a fluid operated pump unit in said bottom hole housing and including a pump body having therein movable fluid operated engine means and pump means operable by said engine means; a valve housing in said bottom hole housing above and in axial alignment with and connected to the upper end of said pump body; a valve tubing above and in axial alignment with and connected at its lower end to said valve housing; a fluid operated valve unit movable downwardly through said valve tubing into said valve housing and including a valve body having therein engine valve means for controlling the operation of said engine means when said valve unit is in said valve housing; passage means in said bottom hole housing and interconnecting said engine means and said engine valve means when said valve unit is in said valve housing; and a pump tubing encircling said valve tubing and connected at its lower end to the upper end of said bottom hole housing.
